UNITED STATES PATENT OFFICE.

KAREL PROKS, OF PRAGUE, AUSTRIA-HUNGARY.

FILTER FOR SIRUPS AND JUICES IN SUGAR-WORKS.

SPECIFICATION forming part of Letters Patent No. 449,271, dated March 31, 1891.

Application filed August 28, 1890. Serial No. 363,281. (No model.) Patented in Germany March 15, 1887, No. 42,355; in Austria-Hungary April 27, 1887, No. 2,155; in Belgium April 30, 1887, No. 77,081; in France August 12, 1887, No. 182,291; in England November 9, 1887, No. 15,322; in Spain March 20, 1888, No. 12,210; in Mauritius April, 1889, and in Russia July 20, 1889, and August 1, 1889, No. 8,375.

To all whom it may concern:

Be it known that I, KAREL PROKS, a subject of the King of Bohemia, Austro-Hungarian Monarchy, residing at Prague, have invented certain new and useful Improvements in Filters for the Filtration of Sirups and Juices in Sugar-Works, (patented in Austria-Hungary April 27, 1887, No. 2,155, tome 37, folio 875; in France August 12, 1887, No. 182,291; in England November 9, 1887, No. 15,322; in Belgium April 30, 1887, No. 77,081; in Spain March 20, 1888, No. 12,210; in Russia July 20 and August 1, 1889, No. 8,375; in Germany March 15, 1887, No. 42,355, and in Mauritius April, 1889;) and I declare the following to be a full, clear, and exact description of the same.

My invention relates to a filter hereinafter described with reference to the accompanying drawings, in which—

Figures 1 and 2 are vertical sections of this filter as used for sirups. Fig. 3 and 4 are details of its frames. Figs. 5 and 6 are vertical sections of my filter as used for juice, and Figs. 7 and 8 are details of its frames.

Similar letters refer to similar parts throughout the several views.

This filter is composed of a hermetically-closed vessel in which there are arranged filtering-frames in greater or less numbers, according to the dimensions of the vessel. Each frame is composed of a corrugated or undulated sheet or plate A A', preferably of tinned iron. The dimensions of these frames vary according to circumstances, being generally about twenty-eight inches square. At the bottom edge and at the two sides the corrugated sheet metal is strengthened by an iron border B of half-round bars bent to a U or may othersimilar suitable shape. The upper edge of the corrugated sheet is inserted in a longitudinal slot in a tube C D, forming a communication with a collecting-gutter H. The tube C D is provided with a ferrule E, which makes a tight joint by bearing against an elastic washer e. This washer is compressed by a screw F. Each frame is covered with a filtering-cloth. The sirup enters a vessel through a tube G, which is provided with a

regulating-valve. The sirup then passes 50 through the filtering-cloth into the grooves or channels in the corrugated plates, whence it is discharged through the tube C D into the gutter H. A tight-fitting closure of any suitable construction enables each of the tubes 55 to be closed and the corresponding frame to be changed when required. The residues of the filtration accumulate at the bottom of the vessel and can be removed through a tube J, provided with a suitable valve. When the 60 filter has been emptied, it can be washed with water introduced through a pipe K, provided with a suitable cock or valve.

In treating certain thick or turbid liquids, steam-injection pipes and an agitator or stirrer may be provided in the lower part of the vessel containing the filtering-frames.

A steam-chamber Z may be provided around the filtering-vessel to keep it warm, if necessary.

Figs. 5, 6, 7, and 8 represent my filter as used for the filtering of juice. In these figures, G is again the tube through which the juice enters. The tubes M and M' serve for the introduction of steam and water to cleanse 75 the different parts inside the filtering-vessel when needed.

Instead of the compressing-screw F, Fig. 1, bolts may be used, which are pressed against the tubes C D by means of spiral springs.

The filtering-cloth can be washed with water to which a certain percentage of soda has been added.

In filtering juice much residue is deposited at the bottom, inside the filters. For this 85 reason we prefer the convergent form of the bottom, as shown in Figs. 5 and 6. In the deepest part of the bottom a conveyer T transports the residue to the tube J, by which it is removed.

I am aware that prior to my invention filters for the filtration of sirup and juice have been made with filtering-frames inside their vessels. I therefore do not claim such a combination, broadly; but

What I do claim as my invention, and desire to secure by Letters Patent, is—

1. In a filter for filtering sirup and juice,

filtering-frames composed of corrugated or undulated plates A A', inserted in tubes C D and covered with filtering-cloth, substantially as set forth with reference to the accompanying drawings.

2. In a filter for filtering sirup and juice, the combination, with corrugated and undulated plates A A', inserted in tubes C D and adapted to receive a filtering-cloth, ferrules E on said tubes, and elastic washers e, of means for compressing said washers, and a conveyer T, substantially as set forth.

3. In a filter for filtering sirup and juice, the combination, with filtering-frames composed of corrugated or undulated plates A A', inserted in tubes C D and covered with filtering-cloth, of ferrules E on said tubes, elastic

washers e, and means for compressing said washers, substantially as and for the purpose set forth.

4. In a filter for filtering sirup and juice, the combination, with the valved entrance-tube G, of filtering-frames composed of corrugated or undulated plates A A', inserted in tubes C D and adapted to receive a filtering-cloth, and steam and water pipes M M', substantially as and for the purpose specified.

In witness whereof I have hereunto set my hand in presence of two witnesses.

KAREL PROKS.
